UNITED STATES PATENT OFFICE.

FREDERICK P. MARX, OF ST. LOUIS, MISSOURI.

SHOE HEEL.

1,419,637.

Specification of Letters Patent. Patented June 13, 1922.

Application filed October 11, 1920. Serial No. 416,196.

To all whom it may concern:

Be it known that I, FREDERICK P. MARX, a citizen of the United States, residing at the city of St. Louis and State of Missouri, have 5 invented a new and useful Shoe Heel, of which the following is a specification.

This invention relates to shoe heels.

An object of the invention is to provide a shoe heel of novel construction and arrangement in which the novel features contribute 10 to the production of a shoe heel superior to others now in use.

Another object of the invention is to provide an improved shoe heel having novel 15 means for securing the heel to the shoe and for supporting a part of the shoe sole in advance of the heel.

Another object of the invention is to provide a shoe heel embodying a tap of novel 20 and advantageous construction.

Other objects will appear from the following description in which I refer to the accompanying drawings, and in which—

Fig. 1 is a plan view of my improved heel 25 with the securing portion of the heel removed.

Fig. 2 is a plan view of the heel with the securing portion in connection therewith.

Fig. 3 is a vertical sectional view taken on 30 a line extending longitudinally through the heel.

Fig. 4 is a vertical sectional view taken transversely of the heel.

Fig. 5 is a view showing the lower surface 35 of the tap.

Fig. 6 is a sectional view showing the preferred construction of the heel extension.

As shown, my improved heel includes a 40 hollow casting 1 which may be of any desired dimensions and style. The front or breast

wall of the heel is formed with an integral forward extension 2 which, in the case of a French heel, extends forwardly and downwardly toward the tread portion of the sole.

The extension 2 constitutes an important 45 feature of the invention and is of such novel shape and arrangement as to constitute a strong support for the sole of the shoe and for the arch of the foot of the wearer for 50 relatively a considerable distance in front of the line at which the front or breast wall of heels have heretofore been made to terminate. The extended portion 2 may be and preferably is formed with a longitudinal depression or groove in its upper surface into 55 which the shoe sole is fitted.

As will be seen by reference to Fig. 6, the upper surface of the extended portion 2 preferably slopes or inclines downwardly or inwardly from the side edges thereof, thereby forming the longitudinal channel or groove mentioned. The extension 2 is formed with a comparatively thin edge at its forward end so that the sole 3, which is secured to the sole proper and which in the case of fine shoes is 60 extended along the front or breast wall of the heel, will rest smoothly where it leaves the extension 2 toward the sole proper. The extension 2 in some cases is preferably extended forwardly from the shoulders 4 which 65 is the farthest point to which the heel structure has heretofore been extended forwardly. In advance of the shoulders 4 the extension 2 is formed with holes 5 through which the fasteners 6 pass into engagement with the 70 shoe sole to form a binding connection between the shoe sole and the heel far in advance of the point at which heels have heretofore terminated.

This construction provides a strong heel, 80 and a proper support for the arch of the foot of the wearer and for the shoe sole far in advance of the heel proper, so that even in the case of French heels the arch of the foot is comfortably supported.

My invention also embodies novel means 85 for securing the heel proper to the shoe. In the embodiment shown lugs 7 are in rigid connection with the walls of the heel. The lugs 7 extend upwardly from an integral 90 union with the walls of the heel a sufficient distance to extend through holes in a metallic plate 8 and through a block 9 of penetrable material such as leather, or fibre, or wood, or other appropriate material capable of use 95 for this purpose.

The plate 8 is arranged to fit within the upper portion of the heel and is preferably dished so as to provide sloping or inclined walls, as will be readily understood by reference to Figs. 3 and 4. The penetrable block 9 even within the dished plate 8 and the lugs 7 extends through both of said parts a sufficient distance to permit the protruding ends of said lugs to be hammered or swaged to 105 form heads to fix the plate and the penetrable block rigidly in position in the upper portion of the heel. Preferably a washer 10 is employed in connection with the lug 7 at the forward wall of the heel and a plate 11 having one or more upwardly and rearwardly 110 projecting tongues 13, is held in rigid posi-

tion by the lugs 7 at the rear portion of the heel. The tongues 12 are arranged to extend into or through slots or openings near the rear end of the shoe sole to clamp the rear end of the sole in rigid union with the heel.

The nails 13 are driven through the shoe sole and through the penetrable block 9. As the nails are driven to position the ends thereof strike the inclined walls of the plate 10 8 and are turned and clinched into the material of the block 9, thereby rigidly binding the heel in connection with the shoe. This novel means of fastening the heel to the shoe constitutes an important feature 15 of my invention in addition to the structure previously described comprising the extended portion 2.

The improved tap constituting an additional feature of the heel comprises a plate 20 14 provided with projections 15 arranged to engage within recesses at the bottom of the heel to prevent the plate from turning. Said plate is preferably formed with an extended sleeve 16 which is received within 25 an appropriate recess in the bottom of the heel proper. A screw 17, passing through the plate 14 and through the sleeve 16 and engaging with the heel proper, may be used to secure the tap in connection with the heel. 30 The lower side of the plate 14 is provided with an inclined flange 18 which is embedded in the tap 19 and which thereby binds the tap in connection with the plate.

The tap thus constructed and arranged 35 is easily removed and replaced. When once secured in proper position it is impossible for the tap to turn, due to the locking engagement of the projections 15 with the heel proper. These elements co- 40 operating with the screw 17 hold the tap from lateral displacement.

From the foregoing it will be seen that I have provided a heel possessing many advantages over those heretofore commonly 45 used. The provision of the arch supporting extension 2 and the binding connections between the same and the shoe sole far in advance of the point at which heels have heretofore been made to terminate, results 50 in many apparent advantages. The additional means of binding the heel to the shoe sole, even up to the rear extremity of the sole also constitute highly advantageous features. The advantage of the novel tap and the securing means therefor is apparent.

What I claim and desire to secure by Letters Patent, is:

1. A shoe heel, comprising a hollow casting 60 in the form of a French heel, having an

integral breast wall, curving forwardly at its upper end, an extension integral with said breast wall, extending forwardly to support the arch of the shoe sole, a separate metallic plate fixed in the upper portion 65 of the heel, a penetrable block secured upon said separate plate, means for holding said plate and said block rigidly in position in the casting, a projection extending upwardly and rearwardly above the rear end 70 of the penetrable block to engage the rear portion of the shoe sole, and a removable tap in connection with the lower end of the heel.

2. A shoe heel, comprising a hollow casting 75 having a breast wall; an extension cast integral with the breast wall extending downwardly and forwardly to support the arch of the shoe; a penetrable block within the upper portion of the casting; a flexible 80 projection near the rear end and above the penetrable block near the rear wall of the casting for engaging the shoe sole near the rear end of the sole; means for holding said block and said projection rigidly in connection with the casting; fasteners passing through the sole and into the penetrable block between said projection and said extension; and fasteners securing the shoe sole and said extension together in 90 front of the penetrable block.

3. A shoe heel, comprising a hollow casting in the form of a French heel having its rear wall extending downwardly and forwardly from the upper portion thereof; an 95 extension integral with the breast wall of the heel extending downwardly and forwardly under the arch of the shoe sole; a projection located near the upper end of the rear wall of the heel for engagement 100 with the shoe sole; means for holding said projection rigidly in connection with the heel; a penetrable block rigidly located in the upper portion of the casting; a separate metallic plate supported in the upper portion 105 of the casting below said block; and fasteners passing through the shoe sole and into said block.

4. A shoe heel, comprising a hollow casting having its walls diverging toward the upper end of the heel; a metallic plate secured within the upper portion of the heel; a penetrable block on said plate for receiving the fasteners holding the heel in connection with a shoe; means for binding said block and said plate together and in rigid position in the upper portion of the heel; and a flexible projection near the rear wall of the heel for engaging a shoe sole.

FREDERICK P. MARX.
